UNITED STATES PATENT OFFICE.

ALBERT A. FROELICH, OF TOLEDO, OHIO.

DEVICE FOR MAINTAINING A CONSTANT SUPPLY OF MELTED MATERIAL IN A RESERVOIR.

1,138,743.

Specification of Letters Patent. Patented May 11, 1915.

Application filed June 29, 1912. Serial No. 706,594.

To all whom it may concern:

Be it known that I, ALBERT A. FROELICH, a citizen of the United States, residing at Toledo, in the county of Lucas and State of Ohio, have invented a certain new and useful Improvement in Devices for Maintaining a Constant Supply of Melted Material in a Reservoir, of which the following is a full, clear, and exact description.

This invention relates to a device adapted to be used in connection with a reservoir for holding a substance, normally solid, but which is maintained in liquid condition by heat, for the purpose of furnishing to the reservoir fresh supplies, in melted condition, of the substance being used, as the material in the reservoir is depleted, and to maintain the quantity of material within the reservoir substantially uniform.

The object of the invention is to provide a device for this purpose, which will operate efficiently and will readily respond to the changes of condition as to the quantity of material within the reservoir so that fresh supplies may be furnished in proper amount and at proper times.

For the purposes of disclosure, I have shown and described the device of my invention as applied to the melting pot of a linotype machine, to furnish fresh supplies of metal to the pot.

Generally speaking, the object of the invention may be defined as consisting in the combination of elements recited in the accompanying claims.

Reference should be had to the accompanying drawings forming a part of this specification, in which—

Figure 1 is a side elevation with portions in section of a melting pot, together with the device for supplying metal thereto; Fig. 2 is a top plan view of the showing in Fig. 1, with the melting pot omitted; and Fig. 3 is a front elevation of the showing in Fig. 2.

A and B represent portions of the frame of a linotype machine, while C represents a melting pot which is mounted in a suitable support D. The particular kind of melting pot and the mounting therefor may be of usual construction and are immaterial, so far as the invention disclosed herein is concerned.

Upon the frame portion A there is mounted a bracket E provided with clamping jaws

F which engage with the frame A and are held in place by a set screw G. From the bracket E there extends a post H, upon which is mounted a platform I. The platform at one portion thereof is provided with an opening which coöperates with the post H and the platform is held with respect to the post H by a suitable clamping device, such as the wing bolt J. The platform is provided with a suitable opening with which coöperates a cylindrical housing K. At the lower portion, the cylindrical housing is provided with flanges L which coöperate with L-shaped flanges M, formed upon the platform I. The flanges M overhang the flanges L when in engagement. The flanges M are of limited extent and the housing K may be removed from the platform by imparting to the housing a turning movement which removes the flanges L from beneath the overhanging portion of the flanges M. One or both of the flanges M may be provided with a slot for coöoperating with a dog N which is pivoted upon the platform I. Normally, the dog engages with a slot in one of the flanges M and holds the housing K against relative movement. Within the housing there is mounted a frame which comprises three or more rods O that are joined to a head P. This frame may be supported within the housing K in any suitable manner. The head P is hollow for the purpose of allowing the insertion of an ingot within the frame, which ingot will be guided and held in proper position by engagement with the rods O. Supported by the platform and within the housing K, is a crucible Q which is provided with a slanting bottom portion and in the side wall has a slot R which extends to the bottom of the crucible.

The ingot which is used in this device is preferably of a cylindrical shape and is made of appreciable length and as before explained, the ingot is placed so as to be guided by the rods O and the bottom portion rests within the crucible Q substantially in the manner represented in dotted lines in Fig. 1. This arrangement relieves of the necessity of continuously supplying small pieces of type metal, as has heretofore been the custom, and furthermore, permits the continuous feeding of ingots, for as soon as one ingot has been sufficiently used, another ingot may be placed in line with the first

mentioned ingot, the latter ingot being held and guided in its movement by the rods O. Beneath the crucible Q is a heating device S which may be of any suitable type, but is 5 preferably of the type wherein a stream of gas as it enters the burner entrains air sufficient for the combustion of the gas. This burner is supported by a bracket T which is suitably mounted upon the platform I.

Upon the post H there is mounted an arm U, the head of which is provided with an opening which coöperates with the post H and is held in place by any suitable securing device, such as a set screw represented at V. At its opposite end, the arm U is provided with an enlarged portion W through which is an opening. Within the opening is a short post X which carries a base Y. 15 Upon the base is mounted a housing z which is secured upon the base in any suitable manner, such as by the use of screw bolts α as suggested in Fig. 3.

Within the housing is a central chamber b from which leads a duct c. Coöperating with this duct is a nipple d which extends from the housing z in proper direction and position to coöperate with the burner S. In the upper part of the housing z is a duct e 25 which communicates with the chamber b by means of a passageway f. Within the passageway f a cylindrical sleeve g is slidably mounted, which is supported from a screw threaded rod h. The sleeve is secured to the rod h by means of a pin i. Above the passageway f, the housing z is recessed to receive a spring j, the opposite end of which spring bears against the sleeve g, and tends to push the same through the passageway f.

40 The threaded rod h extends without the housing z, and coöperates with a hollow threaded member k. The member k is provided with a knurled head by which it may be turned to move the rod, and in this manner, the position of the sleeve g within the opening f may readily be varied, the spring j serving to yieldably hold the sleeve g in its adjusted position. There is a by-pass connection between the duct e and the chamber, which by-pass connection is represented at l. The base Y has formed therein a duct m. Coöperating with the base and extending over the opening for the duct m is a flexible diaphragm n which is held in 45 proper position between coöoperating portions of the base Y and the housing z.

A tube o is mounted at one end in the base Y in a proper manner to coöperate with the duct m. This tube at its opposite end is 50 bent and is mounted in the head of the receptacle p, within which is a chamber. This member p extends within the melting pot C and is adapted to be contacted, at least in part, by the metal within the melting pot. The tube o and chambered mem-

ber p are completely filled with some fluid material which readily expands and contracts under varying heat conditions affecting it, and in the present instance I have found mercury to be suitable for the purpose. The portion of the tube which is remote from the base Y may conveniently be supported in a manner as suggested in Fig. 1, wherein the bent wire q is provided at one end with a portion which engages with the tube and at the opposite end has a downwardly extending portion which extends through an opening in a bracket r which bracket is supported upon the portion B of the frame for the linotype machine. A set screw s is mounted upon the bracket r and is adapted to engage with the wire q for the purpose of holding the same in adjusted position. The adjustability of the receptacle p permits its relation with respect to the melting pot to be varied. The variation of the height of the receptacle p above the base of the melting pot will regulate the height of the melted metal within the pot. This regulation effected by the movement of receptacle p accomplishes the major portion of the necessary regulation, while the final and complete regulation is effected by the variation of the sleeve g as before explained.

95 In linotype machines, the melting pot is pivoted so that it may move into position to supply metal to the type mold. The movement of the metal necessitates that the receptacle p be supported, for otherwise the movement of the metal would cause relative movement of the receptacle, and consequent inaccuracy of operation. A gas supply pipe t communicates with the duct e.

100 The operation of the device is as follows: The chambered member p extends within the melting pot and the fluid metal within the pot contacts with at least a portion of the outer surface of the member p. The heat of the molten metal within the melting pot will be conducted to the mercury within the chambered member p, which will cause the mercury to expand and push the flexible diaphragm n away from the base Y. When this heating is sufficiently great, the diaphragm will contact with the sleeve and close the opening through the sleeve, thus shutting off the normal supply of gas, which as will be understood, passes from the pipe t through the duct e, sleeve g, chamber b, and through the nipple d. However, there will be a small amount of gas pass through the by-pass l which will supply a sufficient amount of gas to the nipple d to maintain a pilot light, so that ignition may be obtained 110 when gas is supplied in the regular manner.

120 It will be understood that the device may be regulated to function in response to any condition within the melting pot which it is desired to maintain by manipulation of the 130

sleeve *g*. That is to say, the lowering or raising of the sleeve *g* will necessitate a greater or less expansion of the mercury to effect the engagement between the diaphragm and the sleeve so as to shut off the supply of gas.

As the metal within the melting pot becomes lower, and less of the surface of the chamber member *p* is contacted by the metal, the mercury is not expanded to such a great extent, and consequently the diaphragm *n* is not expanded so much. The lowering of the diaphragm permits the gas to enter the chamber *b*, and be supplied to the nipple *d*, and in this manner, heat is applied beneath the crucible *Q*, which heating results in the melting of a portion of the ingot which is supported within the housing *K*. As the metal melts, it finds egress from the crucible *Q* through the slot *R* and drops into the melting pot *C*. When the quantity of metal thus supplied to the melting pot has become sufficient so that the metal contacts with a sufficiently large portion of the surface of the chambered member *p*, then the expansion of the mercury again causes the elevation of the diaphragm *n* to shut off the supply of gas. This operation of the device is continuous so long as the machine is in operation.

Attention is called to the fact that the platform *I*, together with the parts carried thereby may readily be swung to such a position as shown in dotted lines in Fig. 2, and thereby afford easy access to the melting pot and to the other portions of the device.

From the foregoing description, it will be apparent that the base *Y* and the post *X* which extends therefrom may be readily removed from the opening through the portion *W* of the arm *U*. This permits the parts which are supported upon the base *Y* to be readily removed, as a unit, so that ready access to the melting pot may be had.

Having thus described my invention, what I claim is:

1. The combination with a reservoir adapted to hold melted material, of a crucible adapted to contain said material in solid form, a device for melting the metal in said crucible, means for controlling the functioning of said heating device, a thermostatic device coöperating with the metal within said reservoir and adapted to be contacted by the material therein, and operative connections between the thermostatic device and the controlling means for the heating device.

2. The combination with a reservoir adapted to hold melted material, of a crucible adapted to contain said material in a solid form, a device for melting the metal in said crucible, means for regulating the functioning of said heating device, a closed receptacle adapted to contain a readily expandable and contractible fluid substance, a por-

tion of said receptacle being adapted to be contacted by the material within the reservoir, one end of said receptacle being closed by a movable member, the said movable member and the controlling means for the heating device being adapted to coöperate to regulate the functioning of the heating device.

3. The combination with a reservoir adapted to hold melted material, of a crucible adapted to contain said material in solid form, a burner for effecting the melting of the metal in said crucible, means for supplying a combustible to said burner, a thermostatic device coöperating with the metal within said reservoir and adapted to be contacted by the material therein, and operative connections between the thermostatic device and means for supplying combustible fluid for controlling the functioning of the burner.

4. The combination with a reservoir adapted to hold melted material, of a crucible adapted to contain said material in solid form, a burner adapted to effect the melting of the metal in said crucible, means for supplying a combustible fluid to said burner, a movable member controlling the passage of fluid to said burner, a thermostatic device coöperating with the metal within said reservoir and adapted to be contacted by the material therein, said movable member being controlled by said thermostatic device.

5. The combination with a reservoir adapted to hold melted material, of a crucible adapted to contain said material in solid form, a burner adapted to effect the melting of the metal in said crucible, a conduit through which a combustible fluid is supplied to said burner, a flexible diaphragm controlling the passage of said fluid through said conduit, a thermostatic device including a closed receptacle having a portion thereof adapted to be contacted by the material within the reservoir, said receptacle being adapted to contain a readily expandable and contractible fluid substance, the said fluid substance within the thermostatic device operating upon the flexible diaphragm to control the movement thereof.

6. The combination with a reservoir adapted to hold material, of a crucible adapted to contain said material in solid form, a burner adapted to effect the melting of the metal in said crucible, a conduit for supplying a combustible to said burner, a movable sleeve forming a portion of said conduit, a diaphragm adapted to engage one end of said sleeve, said diaphragm controlling the passage of combustible fluid through said conduit, a thermostatic device including a closed receptacle adapted to contain a readily expandable and contractible fluid substance, a portion of said receptacle being adapted to be contacted by the material

within the reservoir, the movement of the said flexible diaphragm being controlled by the fluid within the thermostatic device.

7. The combination with a reservoir adapted to hold melted material, of a crucible adapted to contain said material in a solid form, a burner for effecting the melting of the metal in said crucible, a conduit for supplying a combustible fluid to said burner, a movable sleeve forming a portion of said conduit, a flexible diaphragm adapted to engage one end of said sleeve, means for moving said sleeve with respect to said diaphragm, a thermostatic device comprising a receptacle adapted to contain a readily expansible and contractible fluid, a portion of said receptacle being adapted to be contacted by the material within the reservoir, the movement of said diaphragm being effected by the fluid material within the said receptacle.

8. The combination with a reservoir adapted to hold melted material, of a crucible adapted to contain said material in solid form, a burner for effecting the melting of the metal in said crucible, means for supplying a combustible fluid to said burner, said means comprising a casing having a chambered portion, a sleeve extending into said chambered portion, means for regulating the position of said sleeve, a diaphragm within said chambered portion adapted to contact the end of the sleeve, a duct formed in the base of said casing, said duct opening beneath the diaphragm, a thermostatic device comprising a receptacle adapted to contain a readily expansible and contractible fluid substance, said receptacle being adapted to be contacted by the material within the reservoir, said receptacle communicating with the duct formed in the base of the casing, whereby the fluid within the thermostatic receptacle may impinge against the diaphragm.

45 9. The combination of a reservoir adapted to hold melted material, of a crucible adapted to contain said material in solid form, a device for melting the metal in said crucible, means for controlling the functioning of said heating device, a thermostatic device within said reservoir, means for adjusting the height of said thermostatic device within said reservoir, and operative connections between the thermostatic device and the controlling means for the heating device.

10. The combination with a reservoir adapted to hold melted material, of a crucible adapted to contain said material in solid form, a gas burner adapted to effect the melting of the metal in said crucible, a conduit through which gas is supplied to said burner, an adjustable sleeve forming a portion of said conduit, a flexible diaphragm controlling the passage of gas through said conduit and adapted to engage said sleeve, a

thermostatic device including a closed receptacle adapted to be placed within the reservoir, means for varying the height of said receptacle with respect to the reservoir, said receptacle being adapted to contain a readily expansible and contractible fluid substance, the fluid substance within the thermostatic device operating upon the flexible diaphragm to control the movement thereof.

11. The combination with a reservoir adapted to hold melted material, of a crucible supported above the reservoir, and adapted to hold said material in solid form, a guiding frame associated with said crucible, whereby ingots of said solid material may be guided and held in proper relation with respect to said crucible, and means for the melting of the metal in said crucible.

12. The combination with a reservoir adapted to hold melted material, of a crucible adapted to contain said material in solid form having a slanting bottom portion and provided with an opening in the wall thereof, said crucible being supported above the reservoir, means for supporting an ingot of solid material in proper relation with respect to said crucible, and means for melting the metal in the crucible.

13. The combination with a reservoir adapted to hold melted material, of a crucible adapted to contain said material in solid form, means for supporting said crucible above the reservoir, said supporting means being movable upon a pivot whereby the crucible may be moved to afford access to the reservoir, and means for melting the metal in the crucible.

14. The combination with a reservoir adapted to hold melted material, a bracket supported adjacent to the reservoir, a platform pivotally mounted upon said bracket, a crucible carried by said platform, a burner supported from said platform beneath the crucible, the said platform and parts carried thereby being removable to afford access to the reservoir.

15. The combination with a reservoir adapted to hold melted material, of a bracket supported adjacent to said reservoir, a platform pivoted upon said bracket, a crucible carried by the platform, a burner carried by the said platform, means for supplying a combustible medium to said burner, said means being removably mounted upon said bracket.

16. The combination with a reservoir adapted to hold melted material, of a bracket supported adjacent to said reservoir, a platform pivotally supported upon the bracket, a crucible carried by the platform, a burner supported from the platform beneath the crucible, a housing removably carried by said bracket, means for supplying a combustible fluid from said housing to the burner, means for controlling the passage of said

- fluid through the housing, a thermostatic device operatively connected with said means for controlling the fluid, a portion of said thermostatic device being supported within the reservoir, the housing and thermostatic device being removable as a unit.
17. The combination with a reservoir adapted to hold melted material, of a crucible adapted to contain said material in solid form, means for melting the metal in said crucible, a housing surrounding said crucible, a guiding frame within said housing, said frame supporting and guiding an ingot of said solid material in proper relation to the crucible.
18. The combination with a reservoir
- adapted to hold melted material, of a platform pivotally mounted above said reservoir, a crucible adapted to contain said material in solid form, said crucible being supported by the platform, a housing surrounding the crucible, means for detachably securing the housing upon the platform, and means within said housing for guiding the solid material fed to the crucible.

In testimony whereof, I hereunto affix my signature in the presence of two witnesses.

ALBERT A. FROEHLICH.
